TOOL HAVING HANDLE MOVABLE AT RIGHT ANGLES AND DOVETAILED LOCK

Orlie W. Dawson, Ferndale, Mich.

Application December 7, 1946, Serial No. 714,856

5. Claims. (Cl. 145—61)

1

This invention relates to a tool for driving and setting screws, bolts, nuts or the like. Primary objects of this invention are to provide an improved tool for driving and setting screws, nuts, bolts or the like; to provide a tool of the aforementioned type having a handle thereon which is slidably and hingedly associated with the shank of the tool and which can be swung out at right angles to the tool shank and engaged in such position anywhere along said shank; to provide novel means of releasably locking the aforementioned handle in a driving position, that is a position coaxial with said shank; to provide means which will allow the handle, when swung normally to said shank to be rotated thereon without turning the latter so as to provide means of obtaining a new bite for said handle on the shank; to provide a handle so constructed that when the latter is positioned at right angles with respect to the shank it will not slip thereon when the tool is being operated; to provide a tool of the aforementioned type to which various work-engaging tools may be drivingly connected for use in driving and setting any of the various types of screws or for any of the various sized nuts, bolts, or the like; to provide a tool of the aforementioned type which is rugged in construction, inexpensive to manufacture, and neat in appearance.

These and other objects of this invention will become apparent from the following detailed description taken in conjunction with the accompanying drawings, in which

Fig. 1 is a side elevational view of one embodiment of the tool of this invention with the handle disposed parallel to the shank;

Fig. 2 is an enlarged cross-sectional view taken along the line 2—2 of Fig. 1;

Fig. 3 is an enlarged cross-sectional view taken along the line 3—3 of Fig. 1;

Fig. 4 is an enlarged cross-sectional view taken along the line 4—4 of Fig. 1;

Fig. 5 is an enlarged cross-sectional view taken along the line 5—5 of Fig. 1;

Fig. 6 is a reduced side elevational view of the structure illustrated in Fig. 1 with the handles shown at right angles to the shank;

Fig. 7 is a horizontal cross-sectional view of the handle and shank illustrated in Fig. 1 showing a further embodiment of the invention;

Fig. 8 is a broken sectional view of the structure illustrated in Fig. 3 showing a further embodiment of the invention;

Fig. 9 is a side elevational view of the driving end of a tool shank illustrating a further embodiment of the invention;

Fig. 10 is a cross-sectional view of the driving end of the tool of this invention illustrating a removable attachment secured thereto;

Fig. 11 is a cross-sectional view of the structure 60

2

similar to that illustrated in Fig. 10 showing a further embodiment of the invention;

Fig. 12 is a cross-sectional view of the driving end of a tool illustrating a further form of the invention; and

Fig. 13 is a cross-sectional view similar to Fig. 12 illustrating a still further embodiment of the invention.

Referring now to the drawings and more particularly to Fig. 1, it will be seen that the tool of this invention comprises three primary parts, namely, a head element 15 rotatably mounted on the upper end of a tool shank 17 and a handle 19 slidably mounted on said shank. The tool shank 17 is square in cross section throughout the majority of its length, as can be seen in Fig. 1. However, adjacent or near the driving end of the tool the shank 17 is provided with a cylindrical portion 21 which is of substantially the same diameter as the width of the square portion of the shank 17. This cylindrical portion is used for a purpose which will be hereinafter brought out.

As illustrated in Fig. 1, the lower or driving end of the shank 17 is formed with a conventional V-type screw driver end 23 adapted to engage a slotted type screw head for driving and setting the same.

As can be seen in Figs. 9-13, the driving end of the shank 17 can be made with an integral work-engaging tool on the end thereof, or can be made so as to be adapted to receive any of a large number of removable work-engaging tools on the end thereof.

As seen in Fig. 9, the driving end of the shank 17 is formed in the shape of a Phillips screw driver 27 which is adapted for use in driving and setting Phillips-type screws.

In Fig. 10, the driving end of the shank 17 is cut off square as at 29 and is provided adjacent the end thereof with a spring-pressed ball 31. This type of shank driving end is adapted to receive a socket-type tool 32 for driving and setting bolts, nuts and the like. The socket tool 32 is of the type having one socket 33 for receiving the workpiece and a separate socket 34 for receiving the end of the shank 17. The spring-pressed ball 31 retains the socket on the end of the shank 17.

Fig. 11 illustrates the use of a still different type of socket tool on the end of the tool shank. In this embodiment the driving end of the shank 17 is formed with a pair of upset oppositely disposed bumps 34 and is also provided with a spring-pressed ball 35 engaging ball 35. The socket tool 37 is of the type having a single opening 38 extending through the center thereof, and therefore the bumps 34 act as stops for the back end of the socket and the spring-pressed ball 35 holds the socket firmly to the end of the shank 17.

Figs. 12 and 13 illustrate the driving end of the

shank 17 having a square recess 39 formed in the end thereof adapted to receive the square shank 41 of a removable Phillips head screw driver 43, as shown in Fig. 12, and of a removable Allen head screw driver 45, as shown in Fig. 13. Suitable means, such as a spring-pressed ball, are provided on the square shank 41 for holding the tool firmly in the recesses 39 in the end of the shank.

It will thus be seen that this invention contemplates the use of a tool wherein either a solid driving end may be provided for the shank, or the shank may be formed with an end adapted to receive any of the various types of removable working tools which may be used for driving and setting workpieces such as screws, bolts, nuts or the like, with a minimum amount of time required to adapt the tool for use on any of these various workpieces.

As seen in Fig. 3, the upper end of the shank 17 is formed with a cylindrical portion 49, and adjacent the upper end of the cylindrical portion 49 an annular groove 51 of a semi-circular shape is formed. As previously stated, the head element 15 is rotatably mounted to the upper end of the shank 17 and, as illustrated in the drawings, the head element is of a hexagonal shape. The head element 15 has a depending collar 53 on the lower end thereon, and the collar 53 and head 15 are provided with a centrally disposed recess 55 extending upwardly from the lower end of the collar into the head element. Extending upwardly from the recess 55 is a smaller cylindrical recess 59 adapted to rotatably receive the shank cylindrical portion 49 therein. As can be seen in Fig. 4, the head element 15 is drilled angularly across opposite faces thereof to receive a pin 61 therein which is received in a portion of the annular groove 51 cut in the cylindrical shank end 49. The pin 61 rotatably connects the head 15 to the shank 17.

As illustrated in Fig. 8, the head 15 may be rotatably attached to the shank 17 in a still different manner. The upper end of the shank 17 is provided with a cylindrical portion 63 which has its upper end recessed as at 65. The head element 15 is provided with a recess 67, similar to the recess 55 in the previous embodiment, and the upper end of which communicates with a cylindrical aperture 69 of reduced diameter which is enlarged at 71. The cylindrical portion 63 of the shank 17 can then be rotatably secured to the head element 15 by forcing the head element 15 down on top of the cylindrical shank portion 63 so as to flare the upper recessed end of the cylindrical portion 63 outwardly to provide an annular flange 73 which projects into the enlarged portion 71 to prevent the shank from being withdrawn from the head element but at the same time allowing rotation therebetween.

The collar 53 which depends from the head element 15, as can be seen in Fig. 3, has its outer surface inclined downwardly and outwardly to provide the male portion of a dovetail lock, as will be hereinafter described. As can be seen in Fig. 2, the outer surface of the collar 53 is eccentric with respect to the center of the shank 17 as at 54. In the embodiment illustrated in the drawings, this eccentricity or offset amounts to approximately .028 of an inch.

As illustrated in Fig. 1, the handle element 19 is of a generally hexagonal shape and has a square opening 75 extending longitudinally through the center thereof. As best seen in Fig. 3, the handle is provided with a longitudinal rectangular slot 77 cut in one of its sides which

extends from the upper end and terminates in an end wall 79 adjacent to the lower end thereof. The slot 77 also communicates with the opening 75 extending through the center of the handle 19.

5 Diametrically opposed from the slot 77 is a shallow rectangular slot 81 which extends upwardly from the lower end of the handle 19 and terminates in an end wall 83. The slots 77 and 81 are longitudinally aligned and overlap each other so that the distance between the end wall 83, where the slot 81 terminates, and the end wall 79, where the slot 77 terminates, is equal to the width of the slot 75 extending through the center of the handle 19.

10 The handle 19 is slidably received on the square shank 17 but is not rotatable thereon due to the close tolerances between the opening 75 and the shank 17. The upper end of the handle 19 is formed with a generally circular recess 85 therein, which recess is complementarily dovetailed to receive the dovetailed depending collar 53 of the head element 15. The recess 85 likewise is eccentric with respect to the center of the shank 17. It is offset in the embodiment illustrated in the drawing toward the slot as at 86 in Fig. 2 approximately .028, as can be seen in Fig. 2. When the handle 19 is coaxial with the shank 17 it can be slid upwardly into an abutting relation with the head element 15, and locked thereto by rotating the head element until the recess 85 will receive the collar 53 therein. The head element 15 is then turned in either direction and due to the eccentricity of both the recess 85 and the collar 53 the mating surfaces thereof will bind and prevent further rotation. The dovetail lock formed by the collar 53 and recess 85, will lock the handle to the head 15 and retain the handle in a position coaxial with the shank 17. This position is the driving position for the tool and will be referred to as such throughout the remainder of the specification and claims.

15 Due to the slot arrangement previously described for the handle, the handle 19 is hingedly associated at its lower end to the shank 17 and when the handle is released by the head element 15 so that it may be slid downwardly out of engagement therewith, the upper end of the handle can be swung outwardly away from the shank, due to the slot 77 which leaves the upper end thereof open. The handle will swing outwardly until it reaches an angle of approximately 90° with respect to the shank, whereupon the end wall 83, at the end of the slot 81 on the lower end of the handle 15, will abut against one side of the shank 17 and the end wall 79 at the end of the opposite slot 77 will abut against the opposite side of the shank 17 to retain the handle in a position normal to the shank, as illustrated in Fig. 6. The handle 19 may then be slid upwardly or downwardly along the shank 17 to any desired point, so that it is possible to apply force on the tool shank very near the driving end.

20 As can be seen in Fig. 3, the square opening extending normal to the longitudinal opening 75 and formed by the opposed walls 79 and 83, is of the same width as the width of the longitudinal opening 75 so that when the handle is in the outwardly swung position and driving pressure is exerted on the free end thereof, it will be locked to the shank in the position where the pressure is applied. That is, when pressure is applied to the free end of the handle 19, it cannot slide along the shank 17. The handle therefore provides an effective means for driving and rotating the shank

close to the driving end without any danger of the handle slipping along the shank.

When the handle is in the outwardly swung position and is being used to rotate the tool for driving a screw or the like often times the handle becomes rotated to a position where it is difficult or impossible to exert a force thereon. When this occurs, it is possible to rotate the handle with respect to the shank without turning the shank. This is accomplished by sliding the handle along the shank until the lower end thereof is positioned over the shank cylindrical portion 21. The handle can then be rotated without turning the shank. After the new bite has been obtained the handle can be slid longitudinally along the shank until it is over the desired square portion thereof, and then once more it can be used to drive the shank and working tool on the end thereof.

In the embodiment illustrated in Fig. 7, the shank is provided with a longitudinal filler strip 89 which is secured on the face of the shank portion 17 which lies opposite to the slot 77. This strip is provided for the purpose of filling up the slot 77 when the handle is in the driving position, in order to present a neater appearing tool. The strip 89 is secured to the front face of the shank 17 by means of a plurality of countersunk screws 91 inserted through the back face of the shank 17.

While several embodiments of this invention have been illustrated and described, it is to be understood that the invention is not to be limited thereto and that it is intended to cover all modifications thereof which would be apparent to one skilled in the art and which come within the spirit and scope of the appended claims.

I claim:

1. A manually operable tool including a square shank, a handle having an opening extending longitudinally through the center thereof slidably received on said shank, said handle having on one side an elongated slot with an end wall communicating with said opening and on the other side a short slot having an end wall also communicating with said longitudinal handle opening, the end wall of one slot and the end wall of the other slot being so positioned as to define a square opening extending normally to said longitudinal square handle opening adjacent one end of said handle, whereby said handle can be swung outwardly at right angles to said shank.

2. A manually operable tool including a square shank, having a cylindrical portion intermediate the ends thereof, a handle element having a square longitudinal opening through the center thereof slidably received on said shank, said handle having an elongated longitudinal slot extending inwardly from one end and terminating adjacent the other end thereof, said slot also communicating with said square longitudinal handle opening, said handle having a short longitudinal slot extending inwardly from said other end on the opposite side thereof from said first slot, the inner end portions of said slots overlapping and defining opposite sides of a square opening extending through said handle normally to said handle longitudinal opening, whereby said handle is hingedly connected to said shank and may be swung outwardly at right angles to said shank for turning the same when engaging a square portion thereof and turning relative thereto when engaging said cylindrical portion.

3. A manually operable tool including a square shank, a handle element having a square longitudinal opening through the center thereof slidably received on said shank, said handle having an elongated longitudinal slot extending inwardly from one end and terminating adjacent the other end thereof, said slot also communicating with said square longitudinal handle opening, said handle having a short longitudinal slot extending inwardly from said other end on the opposite side thereof from said first slot, the inner end portions of said slots overlapping and defining opposite sides of a square opening extending through said handle normally to said handle longitudinal opening, whereby said handle is hingedly connected to said shank and may be swung outwardly at right angles to said shank for turning the same.

4. A manually operable tool including a square shank, a handle having a square-shaped opening extending longitudinally through the center thereof slidably received on said shank, said handle having on one side an elongated slot with an end wall communicating with said hollow square opening and on the other side a short slot having an end wall also communicating with said longitudinal opening, the end wall of one slot and the end wall of the other slot defining a square opening extending normally to said longitudinal square opening adjacent one end of said handle, whereby said handle can be swung outwardly at right angles to said shank and locked thereto when force is exerted on the free end of said handle, a head element rotatably mounted to the upper end of said shank, and lock means on said head element and handle for securing said handle on said shank in a driving position.

5. A manually operable tool including a square shank, a handle having a square-shaped opening extending longitudinally through the center thereof, slidably received on said shank, said handle having on one side an elongated slot with an end wall communicating with said hollow square opening and on the other side a short slot having an end wall also communicating with said longitudinal opening, the end wall of one slot and the end wall of the other slot being so positioned as to define a square opening extending normally to said longitudinal square opening adjacent one end of said handle, whereby said handle can be swung outwardly at right angles to said shank, a head element rotatably mounted on the upper end of said shank, and off-center annular dovetails formed on the lower end of said head element and on the upper end of said handle element which mate with each other in one position and form a dovetail lock for locking said handle on said shank in a driving position when relatively rotated from said mating position.
